UNITED STATES PATENT OFFICE.

FRANCIS C. MASON, OF GRAND RAPIDS, MICHIGAN.

CASTER-SOCKET.

SPECIFICATION forming part of Letters Patent No. 617,467, dated January 10, 1899.

Application filed May 17, 1898. Serial No. 680,998. (No model.)

To all whom it may concern:

Be it known that I, FRANCIS C. MASON, a citizen of the United States, residing at Grand Rapids, in the county of Kent and State of Michigan, have invented certain new and useful Improvements in Caster-Sockets; and I do hereby declare the following to be a full, clear, and exact description of the invention, such as will enable others skilled in the art to 10 which it appertains to make and use the same.

My invention relates to improvements in caster-sockets, and more particularly to such sockets made of a single integral piece of sheet metal; and its object is to provide the same 15 with certain new and useful features, herein-after more fully described, and particularly pointed out in the claims, reference being had to the accompanying drawings, in which—

Figure 1 is a plan view of the sheet-metal blank before forming; Fig. 2, a side elevation of the socket complete; Fig. 3, a bottom view of the same, and Fig. 4 a vertical section of the same on the line 4-4 of Fig. 3.

Like letters refer to like parts in all of the 25 figures.

In such structures it is essential that there should be a tubular body having a pintle-retainer (usually at the top) and a flange at the bottom to engage the end of the wood in which 30 the socket is inserted. Attempts have been made to draw the tube from the metal of the center of a disk, the outer part of the disk forming the flange; another to turn the flange outward on the end of a tube. Both are difficult and expensive and the amount of metal 35 available is insufficient. It has been proposed to form others from a sheet-metal blank adapted to be doubled upon itself in two semi-cylindrical parts, having other parts forming 40 the flange. These are unstable in form, wasteful of material, and open to other minor objections. It has also been proposed to form the device from a substantially rectangular piece of sheet metal slitted longitudinally 45 and the slitted portions turned outward at a right angle to serve as a flange and with radiating convex surfaces. This form is unsubstantial and there is great tendency to break and pull apart at the junction of the tube and 50 radial parts and there is not sufficient bearing for the yoke of the caster. Pintle-retainers are usually formed by longitudinally slit-

ting or dividing the tube and bending the upper part inward. Chips from boring the holes or other obstructions are liable to get 55 behind these parts, and, having no escape, interfere more or less with their action or cause them to be inoperative. To remedy these defects, I provide a blank of sheet metal of peculiar form, which when rolled and stamped 60 into proper shape will produce a tubular body adapted to fit closely within the wood and formed with a single longitudinal seam and having at its lower end a continuous annular half-round outwardly-extended bead which 65 gives strength at this point and distributes the stretch and drawing of the metal, also prevents cracking and weakening at the junction of the flange with the tubular body, and also provides a sufficient bearing for the yoke 70 of the caster and radial portions extending outward to engage the surface of the wood and provide sufficient flange-surface to prevent forcing the socket inward by the weight thereon.

The improvement in the pintle-retainer consists in providing a short tubular upper portion of less radius than the body and separated therefrom by a transverse slot and having a single longitudinal seam and vertical sides. This will expand and let the head pass through and will permit the escape 85 of any obstructions through the slot that may get between this upper portion and the wood.

The blank is made of suitable sheet metal, 85 preferably soft steel, and consists of a substantially rectangular portion A, across the lower end of which portion is a narrow transverse portion B, having projections B'' B''' at the respective ends thereof, and extending 90 laterally from the lower side of the portion B are a number of triangular portions C C C, (preferably three in number.) Above the portion A are transverse slots D D, above which is a transverse portion E, which extends to a distance somewhat less than the width of the portion A. The described blank is formed by suitable stamps and dies into the shape shown in Figs. 2, 3, and 4, the portion A of the blank forming the solid tube A' 95 to receive the pintle of the caster and having but a single longitudinal seam in its side. The portion B forms a bead B' at the bottom of said tube, which bead provides a suitable

bearing for the head of the yoke in which the 5
caster-wheel is journaled and also forms a
stiff rim around the lower end of the socket
to engage the wood in which said socket is in-
serted and having little tendency to break at
its junction with the tubular portion. The
triangular portions C' are left flat and serve
to engage the bottom of the wood and afford
an effectual bearing-surface to keep the socket
10 from being forced upward by the pressure of
the load, and the portions B afford material
to complete the bead B' at the seam. The
points C'' of the triangular portions form
spurs to enter the wood and hold the socket
15 from coming out, and the inwardly-turned
arms of the portion E form springs to engage
the neck of the caster-pintle and detachably
retain the same in place, allowing anything
that may get behind them to escape down-
20 ward through the slots D D. It will be ob-
served that there is no inclined yielding por-
tion whatever behind which anything can
lodge and that the yielding parts of the pintle
retainers are vertically separate from the tube
25 and inside the plane thereof.

Having thus fully described my invention,
what I claim, and wish to secure by Letters
Patent, is—

1. In a caster-socket, a tube formed of a
30 single piece of sheet metal and having but one
longitudinal seam, an annular bead at one end
thereof and integral therewith at its inner
edge, and flat radially-projecting portions in-
35 tegral with the outer rim of the bead and de-
tached from each other at their adjacent
sides, substantially as described.

2. In a caster-socket, a tube formed of a sin-
gle rectangular piece of metal and having a
40 single longitudinal seam, an annular bead
integral with said tube at its inner edge, flat
triangular portions extending radially from
the outer rim of said bead and integral ther-
ewith and detached from each other at their
45 adjacent sides and having their outer angles
turned upward, substantially as described.

3. In a caster-socket, a tubular body hav-
ing a suitable flange at its lower end, and a
pintle-retainer at its upper end consisting of
50 a transversely-separated tubular extension of
less diameter than said body and in parallel
planes therewith, and having a single longi-

tudinal seam at one side and a rigid connec-
tion with said body, said connecting portion
also being in line with the side of the said
body, substantially as described. 55

4. In a caster-socket, a tubular body formed
of a single rectangular piece of sheet metal
and having a single longitudinal seam, a
transverse slot near the upper part of the
same severing the side having the seam and
leaving a connecting portion opposite the
seam and in line with the balance of the tube,
the portion of the tube above said slot being
of less radius than the portion below the same
and flexible at each side of the seam, substan- 60
tially as described. 65

5. A caster-socket consisting of a single in-
tegral piece of sheet metal having a tubular
body having a single longitudinal seam and
having a transverse slot leaving a narrow con- 70
necting portion, said portion being in line
with the said body, the portion above the slot
being of less radius than the portion below
the same, an integral outwardly-extended
75 bead at the lower end of said tube, and tri-
angular portions extending outward from the
bead and having their ends turned upward
at right angles, substantially as described.

6. As an article of manufacture, a blank
for caster-sockets consisting of a single piece 80
of sheet metal having a rectangular body por-
tion to form a tubular body with a single lon-
gitudinal seam, a transverse portion to form
a bead and having end extensions to complete
the bead at the seam, and divided portions 85
extending laterally from said transverse por-
tion to extend radially from said bead, sub-
stantially as described.

7. As an article of manufacture, a blank
for caster-sockets consisting of a piece of sheet 90
metal having a rectangular portion, a T-
shaped portion at one end thereof, a trans-
verse portion at the other end thereof having
end extensions, and triangular portions ex-
tending laterally from said transverse por- 95
tion, substantially as described.

In testimony whereof I affix my signature
in presence of two witnesses.

FRANCIS C. MASON.
